UNITED STATES PATENT OFFICE.

CHARLES A. PUCKETT, OF BROOKLYN, NEW YORK.

SUPPORTING-TABLE.

1,106,057.

Specification of Letters Patent.

Patented Aug. 4, 1914.

Application filed March 19, 1913. Serial No. 755,457.

To all whom it may concern:

Be it known that I, CHARLES A. PUCKETT, a citizen of the United States, residing at Brooklyn, in the county of Kings and State 5 of New York, have invented certain new and useful Improvements in Supporting-Tables, of which the following is a specification, reference being had to the accompanying drawings.

10 This invention relates to new and useful improvements in supporting standards or tables and more particularly to a stand which is adapted to be arranged within the sink to support the dish pan in spaced relation with the bottom of the sink, the object 15 of the invention being to provide a stand or table, which is adapted to support the dish pan out of contact with any greasy slops or waste, which may be poured into the sink.

20 Another object of this invention is to provide a device of this character which will possess advantages in points of efficiency and durability, is inexpensive of manufacture and at the same time is simple in construction and operation.

25

With the above and other objects in view, the invention consists in the novel features of construction and the combination and the arrangement of the parts to be hereinafter 30 more fully described, pointed out in the claim and shown in the accompanying drawings, in which—

Figure 1 is a perspective view of a supporting table constructed in accordance with 35 my invention; and Fig. 2 is a longitudinal sectional view.

Referring more particularly to the drawings, 1 indicates the top of the table which is constructed of galvanized sheet iron or 40 any other suitable material of this character, the marginal portions of which are flexed to afford the downwardly projecting flanges

2. Formed at one side of the top and centrally arranged is a suitable opening 3 which 45 may be used as a drain opening when the device is in use or may be used to receive a nail or hook for suspending the table from

the wall when the device is not in use. Arranged at each corner of the top 1 are the tubular supporting legs, 4, said supporting 50 legs being soldered or otherwise secured to the top and further braced by means of the angular corner pieces 5, the upper ends of which are soldered or riveted to the downwardly projecting flanges 2 and the lower 55 ends thereof tapered and secured to the legs 4 upon the outer sides thereof whereby it will be readily observed that a convenient and effective means is provided whereby adjacent ends of the flanges are held against 60 separation or distortion.

Arranged within the lower end of the tubular supporting legs 4 are the shanks 6, which are formed integral with the supporting feet 7, said shanks and feet being preferably constructed of rubber, as shown in the accompanying drawings, so that when the device is placed in a sink lined with enamel or other similar material, the same will not become marred or scratched by the 70 constant moving about of the table. In washing dishes, it is a very convenient custom to place the dish pan in the kitchen sink on account of the convenience to the drain board, but many objections are made to this 75 operation on account of the sink being too low.

It is the principal object of my invention to support the dish pan at a sufficient height so that the bottom of the dish pan will be 80 practically upon a level with the drain board. It will also be apparent that the dish pan is supported in spaced relation with the sink so that any greasy waste, which may be placed in the sink will not 85 come in contact with the dish pan. It will also be apparent that my device is extremely simple in construction and can be manufactured at comparatively low cost.

While I have shown and described the preferred form of my invention, it will be obvious that various changes in the details of construction and in the proportions may be resorted to for successfully carrying my in-

vention into practice without sacrificing any of the novel features or departing from the scope of the appended claim.

What I claim is:—

5 A device of the character described including a top having its marginal portions flexed to form depending flanges, supporting legs soldered to the top and the inner faces of the flanges at adjacent ends of such 10 flanges, and angular brace plates soldered to

the outer faces of the flanges at adjacent ends and overlying and soldered to the supporting legs whereby such flanges are held against distortion.

In testimony whereof I hereunto affix my 15 signature in the presence of two witnesses.

CHARLES A. PUCKETT.

Witnesses:

ADOLPH F. LOEFFLER,
CHAS. THOMPSON.
